UNITED STATES PATENT OFFICE.

ANTON MAE, OF NEW HAVEN, CONNECTICUT.

PARALLEL-JAW PLIERS.

1,351,668.

Specification of Letters Patent. Patented Aug. 31, 1920.

Application filed November 4, 1919. Serial No. 335,636.

To all whom it may concern:

Be it known that I, ANTON MAE, a citizen of the United States, residing at New Haven, in the county of New Haven and State of Connecticut, have invented certain new and useful Improvements in Parallel-Jaw Pliers, of which the following is a specification.

This invention relates to improvements in combination tools, and more particularly to a type of combination tool embodying wire cutters associated with a pair of parallel plier jaws.

The principal objects of the present invention are: first, to provide a pair of simultaneously operated wire cutters associated with a pair of parallel plier jaws, in order to effect actuation of the wire cutters upon movement of the plier jaws; and second, to so arrange the wire cutters with the plier jaws that multiple leverage will be obtained for increasing the biting power of the wire cutters, and to accomplish this end the leverage afforded by the handles of the device is compounded by the actuating members associated with the jaws, thus materially simplifying the construction of the tool and increasing its efficiency.

Furthermore the tool is so constructed that its fragile parts are all concealed, so that possibility of accidental disarrangement or breakage is reduced to a minimum.

With these and other objects in view, the invention consists in certain novel combinations and arrangements of the parts as will more fully appear as the description proceeds, the novel features thereof being pointed out in the appended claims.

Attention is invited to my prior Patent #1,313,399, issued August 19, 1919, on pliers, upon which the present invention is a modification and an improvement.

For a full understanding of the invention reference is to be had to the following description and accompanying drawings, in which:

Figure 1 is an enlarged perspective view of the jaw portion of the device,

Fig. 2 is a side elevation of the pliers,

Fig. 3 is a transverse sectional view through one of the handles of the pliers showing in detail the connection of the jaw portion and the assembled relation thereof, and

Fig. 4 is a fragmentary perspective view in section showing in detail the wire cutter mounted in the jaw portions.

In the drawings wherein like characters of reference indicate like or similar parts throughout the several views, A and B designate a pair of parallel plier jaws, each provided with the usual serrated surface C for frictionally engaging an object placed between the pair of jaws. Reduced extensions 1 and 2 formed on the respective jaws opposite the noses thereof and having their opposed edges cut away, are slidably carried in sleeves 3 which are pivotally mounted as at 4 in the grip portions of the handles A' and B' and have retaining bars 5 mounted therein for an obvious purpose.

As both the jaws A and B differ materially in certain details of construction I shall take them up separately for the sake of clarity and then describe their combined operation in order to show how other parts of the invention (hereinafter described) are associated with them. Referring particularly to the jaw B, a substantially arcuate arm 6 is formed thereon adjacent the reduced extension 2 thereof, and has the edge thereof opposed to the outer edge of the jaw ground on both sides to provide a knife edge 7 which constitutes one of the elements of one of the wire cutters, hereinafter described in detail. Adjacent the arm 6 and in line with the knife edge 7 is a dovetailed groove 8 adapted for reception of an arm 9 secured within a dovetail recess in the jaw A, as at 9' and provided with a knife edge 10 in registration with the knife edge 7 on the arm 6.

The outer edge of the jaw A is ground down at both sides to form a knife edge 11 which is adapted to coact with a knife edge 12 formed on the auxiliary jaw member 13 which has its reduced shank 14 mounted on a pin 15 carried between the ears 16 formed on the lateral extension 17 on the jaw A. The arm 18 on the jaw B is received within a reduced portion 19 in the jaw A and engages the shoulder formed thereby to lie flush with the outer surface thereof, and is pivoted as at 20 to the end of the shank 14 of the auxiliary jaw 13 whereby to move the same upon actuation of jaws A and B.

The bifurcated handle elements A' and B' are crossed and the arms of the bifurcations α and β thereof are pivoted as at 21 and secured by pins 22 to the jaws A and B respectively, suitable openings 23 being provided in the jaw members for receiving the pins as illustrated in Fig. 1.

The arms α are struck outwardly for a

distance to receive the arms y and close the ends of both arms x and y to lie substantially in the same plane with each other and contiguous to the surfaces of the jaws A and B respectively.

In assembling the device, the arm 9 of the jaw A is placed in the dovetailed groove 8 of the jaw B and the auxiliary jaw 13 is positioned and secured by the pin 15 between the ears 16 with its shank 14 pivotally engaged by the arm 18 on the jaw B.

The knife edge 12 will consequently be in registration with the knife edge 11 on the jaw A. The handle elements are then crossed and secured as at 21 and the extensions 1 and 2 of the jaws A and B placed in the sleeves 3 pivoted in the grip sections thereof. The handles A' and B' are then secured as at 22 to the jaws A and B.

In operation upon moving the jaws A and B the arm 9 is moved in the dovetailed groove 8 into engagement with the knife edge 7 on the arm 6 thus cutting any wires that would be disposed therebetween and in the same operation the auxiliary jaw 13 is moved so that the knife edges 11 and 12 engage for a like purpose.

While I have shown and described the preferred embodiment of my invention it will be understood that minor changes in construction, combination and arrangement of parts may be made without departing from the spirit and scope of the invention as claimed.

What I claim is:

1. The combination in pliers having relatively movable jaws, one of which is provided with a knife edge; of an arm on one of the jaws having a knife edge, a second arm having a knife edge on the other jaw and adapted to approach the knife edge on the first jaw upon relative movement of the jaws, an auxiliary jaw having a knife edge, and means connected with the jaws for moving the same relative to each other and actuating the auxiliary jaw to approach the knife edge of the first-named jaw.

2. The combination in pliers having relatively movable jaws, one of which is provided with a knife edge; of an arcuate arm on one of the jaws ground to form a knife edge, an arm on the other of the jaws ground to form a knife edge and adapted

to approach the first-named arm on movement of the jaws relative to each other, an auxiliary jaw having a knife edge and connected with the second-named jaw, and means for actuating the jaws whereby the knife edge of the auxiliary jaw is moved to approach the knife edge of the first-named jaw.

3. The combination in pliers having relatively movable jaws, one of which is provided with a knife edge; of an arcuate arm on one of the jaws ground to form a knife edge, an arm on the other of the jaws ground to form a knife edge and adapted to approach the first-named arm on movement of the jaws relative to each other, an auxiliary jaw pivotally mounted on the first-named jaw having a knife edge and pivotally connected with the second-named jaw, handle elements connected with the jaws, and collars in the handle elements for slidably mounting the jaws therein.

4. The combination in pliers having relatively movable jaws, one of which is provided with a knife edge; of an arcuate arm on one of the jaws ground to form a knife edge, an arm on the other of the jaws ground to form a knife edge and adapted so approach the first-named arm on movement of the jaws relative to each other, ears formed on an extension of the first-named jaw, an auxiliary jaw pivoted between the ears on said first-named jaw, a second arm on the second-named jaw pivotally connected with the auxiliary jaw, and means for actuating said jaws whereby the respective knife edges are caused to approach one another to sever an intervening wire.

5. In pliers of the character described, relatively movable jaws, one of said jaws being provided with a knife edge, an arm pivotally supported upon the jaw having the knife edge and provided with a companion knife edge to coöperate with the latter, means actuating the arm and acted upon by the other jaw to effect the approach of the knife edges toward each other, and means for actuating the jaws for the opening and closing thereof.

In testimony whereof, I affix my signature hereto.

ANTON MAE.
